US0D1020789S

(12) **United States Design Patent** (10) Patent No.: **US D1,020,789 S**
(45) Date of Patent: ** Apr. 2, 2024

(54) **DISPLAY SCREEN OR PORTION THEREOF WITH GRAPHICAL USER INTERFACE**

(71) Applicant: **Canva Pty Ltd**, Surry Hills (AU)

(72) Inventors: **Cameron Adams**, Sydney (AU); **Jess Ruyter**, Newcastle (AU); **Jacob Thomas Grainger**, Sydney (AU); **Marc-Antoine Roy**, Sydney (AU)

(73) Assignee: **Canva Pty Ltd**, Surry Hills (AU)

(**) Term: **15 Years**

(21) Appl. No.: **29/782,226**

(22) Filed: **May 5, 2021**

(51) LOC (14) Cl. **14-04**

(52) U.S. Cl.

USPC **D14/486**

(58) **Field of Classification Search**

USPC D14/486-495

CPC G06F 3/0481; G06F 3/0486; G06F 3/0485; G06F 2203/04806

(57) **CLAIM**

The ornamental design for a display screen or portion thereof with graphical user interface, as shown and described.

DESCRIPTION

The sole FIGURE is a front view of a display screen or portion thereof with graphical user interface showing our new design.

The dash-dash-dash lines illustrate text, icons, or the remainder of the graphical user interface and form no part of the claimed design. The dash-dot-dash lines depict a boundary line of a display screen or portion thereof, and form no part of the claimed design.

1 Claim, 1 Drawing Sheet
